[57]

ABSTRACT

A removable cover for a shipboard lashing socket that provides a generally cruciform access opening flush with the deck. The cover has a plate which totally covers the cruciform opening and the underside of which has a locator that fits into one leg of the opening and prevents rotation. A central housing portion on the underside of the plate has opposed, horizontal bores each containing a rotatable ball detent, a retainer, a ball seat and a spring biasing the seat and ball detent to its protruding position. The ball detents in an installed cover latchingingly engage the lower edge of the flush deck portion of the socket between adjacent legs of the cruciform opening.

FIG. 5

LASHING SOCKET COVER

This invention relates to lashing sockets for shipboard use to secure aircraft, vehicles and the like, and more particularly to covers for such sockets.

It is, of course, necessary to tie down objects having any considerable weight when they are carried aboard ship; otherwise the natural pitch and roll of the ship on the open seas would cause shifting of such objects that would likely result in damage to the object itself, as well as potential damage to the structure of the ship. Various types of lashing-sockets are presently provided in the decks of ships for this purpose. However, the holes in the decks which result from the installation of such lashing sockets create collection points for water and for trash and are also considered to be a safety hazard to personnel who may trip by catching a toe in such a hole. Attempts have been made to provide covers for shipboard lashing sockets, but to date, such covers have not resisted inadvertent removal under impact of vehicles or when subjected to helicopter airwash and/or wave action upon the flooding of the decks.

It is the object of the present invention to provide improved covers for shipboard lashing sockets. Another object is to provide an easily installable cover for shipboard lashing sockets which will stay in place and resist inadvertent removal. A further object of the invention is to provide a cover for shipboard lashing sockets which will resist the entry of water even in the form of wave action, flooding and hose pressure. These and other objects of the invention will be apparent from the following detailed description of a preferred embodiment of the invention, particularly when read in conjunction with the accompanying drawings wherein:

FIG. 1 is a bottom view of an improved lashing socket cover embodying various features of the invention;

FIG. 2 is a fragmentary view of a vehicle lashing socket installed in the deck of a ship;

FIG. 3 is a sectional view of the cover shown in FIG. 1, taken along line 3—3 thereof;

FIG. 4 is a sectional view of the lashing socket of FIG. 2, shown with a portion of a lashing hook depicted in phantom; and

FIG. 5 is a sectional view enlarged in size taken generally along line 5—5 of FIG. 2 with the cover of FIG. 1 inserted in the lashing socket.

Depicted in the drawings is a lashing socket cover 9 that is designed to fill and plug a lashing socket 11 of the design depicted in FIG. 2. Although the socket is sometimes hereinafter referred to as a vehicle lashing socket, it should be understood that it might be used to tie down any objects. As best seen perhaps in FIGS. 4 and 5, the lashing socket 11 is formed from a body portion 13 having the shape of a shallow bowl and a disk 15 that is suitably attached, as by welding, to the shallow bowl portion. The socket 11 is designed to be suitably installed in a circular hole cut in the metal deck 17 of a ship, wherein it may be affixed as by welding.

In the illustrated embodiment, the socket disk 15 is formed with a central cut-out or access opening of cruciform or four-leaf clover-like design 19 which provides four lobes 21 arranged at 90° orientation to one another which are separated by projections 22. The central portion of the cruciform opening 19 is enlarged in size by appropriately rounding the projections, so as to provide a central opening of a greater dimension

than any of the individual lobes 21. The socket 11 is designed for use with lashing hooks 23 (see FIG. 5) having enlarged heads 25 which will fit through the enlarged central opening and then become entrapped when the hook is moved into one of the lobes 21, as illustrated in FIG. 4.

The cover 9 is formed of a design complementary to the cruciform opening 19, which it closes, but of slightly larger dimension so as to completely overlie the opening and extend a short distance outward of the periphery thereof in all directions. Generally, the cover 9 has a main, flat plate section 31 which is X-shaped and carries depending projections that extend into the socket opening 19 and cooperate therewith for retaining the cover 9 in place. Although other constructions might be used, the cover 9 is usually made as a casting so that the projections in question are formed integrally with the main plate section 31. More specifically, the cover 9 includes a central keeper section 33 plus a pair of arcuate, locator projections 35 which are proportioned to fit within the rounded ends of a pair of oppositely disposed lobes 21 in the socket access opening. In addition, each of the four arms of the X-shaped cover 9 is provided with a reinforcing rib 37 which extends radially outward from the central keeper section.

The keeper section 33 includes a housing 39 which is generally cruciform in shape, although it could have any other suitable shape, for instance, round, because it is proportioned to fit within the central portion of the access opening 19. The keeper housing contains four horizontal bores 41 each oriented at 90° to one another. Each of the bores 41 carries a ball detent 43 which is designed to hold the cover 9 tightly in place in the lashing socket 11 once it has been installed.

In this respect, each of the bores 41 is located at an angle of 45° to the central ribs 37, which are aligned with the legs of the X-shaped plate 31; and thus, the bores 41 each face one of the rounded inner edges of the projections 22. As shown in FIG. 5, each of the ball detents 43 is part of a spring-loaded unit that can be press fit into the bore 41 of the keeper housing. Each of these units includes a cylindrical casing 45 and a compression spring 47 which fit around the rear end of a ball seat 49. This seat 49 has a concave front surface which is matched to the curvature of the ball detent 43 and is entrapped in the unit by folding or crimping the front end of the casing 45 slightly inward after the spring, seat and ball are installed.

As best seen in FIG. 1, the underside of the flat plate section 31 is formed with a shallow groove 51 that extends around the complete periphery of the X-shaped plate. The shallow peripheral groove 51 is positioned so that, when the cover 9 is installed in the socket 11, it will lie just outward of the outline of the cruciform access opening 19. Preferably, a gasket 53 of silicone rubber, or the like, is located in the shallow groove 51 prior to installation of the cover. The gasket 53 may be formed-in-place by using a product such as "Silmate", a liquid silicone rubber marketed by G.E., and it is intended to assure a water-tight seal which is created about the entire periphery of the access opening 19.

The cover 9 is easily installed by aligning the X-shaped plate portion with the cruciform access opening 19 of the socket so that the arcuate locators 35 are received within the curved ends of a pair of opposite lobes 21. When so aligned, the cover is pressed downward into place, forcing the ball detents 43 inward

against the springs 47 as the detents engage and move downward past the upper curved edges of the socket projections 22. The ball detents 43 are preferably made of a rust-resistant material, such as stainless steel, and the possibility of binding is obviated because the balls rotate easily in the concave seats 49 as the cover is forced downward. Once the cover 9 has been pressed inward to its full depth, the ball detents 43 snap back outward, biased by the compression springs 47, into contact with the undersurface of the projections 22 (as shown in FIG. 5), latching the cover 9 securely in place.

The weight of the cover 9, plus the force provided by the four compression springs 47, compress the gasket sealant 53 located in the shallow groove 51, and thus provide a tight seal about the entire periphery. The cover 9 will stay in place and seal the access opening in the socket 11 against entry of water even after subjected to heavy wave action or flooding to a substantial depth, or to propeller wash of a helicopter, or to the impact of heavy vehicles that may be repeatedly moved over such sockets on the deck of a ship where vehicle traffic may occur frequently.

When a socket 11 is needed for use in tying down an object, the cover 9 is removed by means of access notches 57 provided in the underside of the plate portion 31 of the cover. The notches 57 are located outward of the groove 51 at the junctions between the legs of the X-shaped plate and provide clearance in this region above the surface of the deck for the insertion of the tip of a screwdriver, or the like, which can be used to easily pry the cover from its installed position.

Modifications may be made to the illustrated embodiment as would be obvious to one having the ordinary skill in the art, and such modifications are considered as coming within the scope of the invention which is defined by the claims appended hereto. For example, rather than employ four spring-loaded ball detents, a pair of oppositely disposed detents may be used to achieve the desired objective of the invention.

Various of the features are set forth in the claims which follow.

What is claimed is:

1. A removable cover for a shipboard lashing socket having a flush deck portion wherein a generally cruciform access opening is provided having four lobes the outer ends of which are arcuate and having a bottom

portion of generally bowl-like shape which is attached along its periphery to said deck portion, which cover comprises

5 a plate portion of dimension greater than said cruciform access opening which totally covers said opening,

the underside of said plate having a pair of depending locators which are arcuate in horizontal section and are proportioned to fit just within the arcuate outer ends of opposite lobes of said cruciform opening and thereby align said plate portion to totally cover said opening and prevent relative rotation of the installed cover,

said cover having a housing portion depending from the underside of said plate portion and centrally located thereupon,

said housing having at least two opposed, horizontal bores,

each of said bores containing a rotatable ball detent and retainer means limiting the distance said ball detent can protrude from said bore,

seat means in each said bore in contact with a rear portion of each ball detent, and

spring means biasing said seat and ball detent to the protruding position,

said bores being located in said housing so that said ball detents in an installed cover latchingly engage the lower edge of the flush deck portion of the socket in a region thereof between adjacent lobes of the cruciform access opening,

whereby said removable cover is securely latched within said shipboard lashing socket and resists inadvertent removal.

2. A removable cover in accordance with claim 1 wherein the underside of said plate portion is provided with a shallow peripheral groove which locates a gasket for creating a water-tight seal between said installed cover and the socket.

3. A removable cover in accordance with claim 2 wherein said plate portion is generally X-shaped and, at the junctions between the legs of the X, there are provided lifting access notches in the underside of said plate portion, which notches are located between said shallow groove and the outer peripheral edge of said plate portion.
